No. 645,025.

M. LA G. STREETER.
BELT BUCKLE.

Patented Mar. 6, 1900.

(Application filed Oct. 20, 1899.)

(No Model.)

UNITED STATES PATENT OFFICE.

MARGARET LA GORCE STREETER, OF WASHINGTON, DISTRICT OF COLUMBIA.

BELT-BUCKLE.

SPECIFICATION forming part of Letters Patent No. 645,025, dated March 6, 1900.

Application filed October 20, 1899. Serial No. 734,246. (No model.)

To all whom it may concern:

Be it known that I, MARGARET LA GORCE STREETER, a citizen of the United States, residing at Washington, in the District of Columbia, have invented certain new and useful Improvements in Belt-Buckles, of which the following is a specification.

This invention relates to buckles, and particularly to belt-buckles; and the object of the invention is to provide a wire buckle for ribbon or fabric belts, as are universally worn by ladies, with such peculiar construction and arrangement of the working parts that a twisted pivoted bail or anchor having teeth to hold one end of the belt and a twisted tongue having prongs or teeth pointing in the same direction as the anchor-teeth and pivoted to swing independent of the said anchor or bail.

In the accompanying drawings, forming part of this application, Figure 1 shows the practical application of my buckle, the free end of the belt being tucked behind the buckle-frame. Fig. 2 is a front view of the buckle, showing the free end of the belt standing out therefrom. Fig. 3 is a perspective view of the working parts of the buckle. Fig. 4 is a modification looking at the front of the buckle, the frame of which is partly broken away. Fig. 5 is a rear view of a still further modification.

The same numeral-references denote the same parts throughout the several views of the drawings.

The buckle-frame 1 has suitable top and bottom ornamentations 2, which cover bearings 3, and end ornaments 4. The frame may be studded or otherwise further ornamented, as desired. The bail or anchor is composed of two wires 5, one end of each wire being formed into an eye 6, the wires then being given the inward bend 7, the outward bend 8, and projected toward each other in a curve 9, at the terminus of which the wires are twisted together, the ends of the wires being bent back upon their respective curved portions 9 and then away therefrom and terminate in anchor-points 10, to which is attached or anchored one gathered end of a belt 11. The bends 7 of the anchor confine the said folded or gathered end of the belt in the bow formed by the bends 8 in attaching or secur-

ing the belt around the waist, and the said bow permits the waist portion of the belt to be spread out, as fancy or necessity may dictate.

The buckle-tongue is formed of two pieces of wire 1^a, each having a pintle or pivot end 12, which engages the eyes 6 and the frame-bearings 3 to permit the anchor and the tongue 13 to swing separately and independently of each other and of the buckle-frame. The tongue-wires 1^a meet opposite the center of the anchor portion and are twisted together at 13, whence the ends of the wire are extended outward 14 and terminate in sharp prongs 14, pointing in the same direction as the anchor-points 10. The tongue-points have their bearing upon the outside of the buckle-frame, and the anchor makes its bearing upon the inside opposite end of the said frame, so that the free end of the belt, after having been caught by the tongue, is inserted between the anchor and the frame, where it may be entirely hidden, as shown by Fig. 1, or left standing out, as shown by Fig. 2. This is owing to the advantage of the tongue and the anchor being independently pivoted relative to each other and to the buckle-frame, permitting the latter to be raised to admit of said insertion after the belt is in position.

The modification, Fig. 4, depicts a tongue 15, having an eye 16, by means of which it is pivoted on a shaft 17, secured at the ends in a buckle-frame, the anchor being pivotally hung from the said shaft 17 independent of the tongue and spaced by sleeves 18.

The form of buckle shown in Fig. 5 has an anchor or bail 24, provided with pintles 25, to turn in the frame-bearings, and the tongue 26 has eyes 27 engaging the said pintles, whereby the tongue is free to swing upon the pintles independent of the anchor.

It will be observed that the preferred shape of the anchor and of the tongue is maintained throughout the several modifications, though they may be varied according to the shape of the buckle-frame.

It is obvious that any of the buckles here disclosed may be used in other garment fastenings or supports and for ornamentation and use upon hats and bonnets without sewing or tacking.

Having thus described my invention, what

I claim as new, and desire to secure by Letters Patent, is—

1. A buckle having a suitable frame, and composed of a twisted wire member forming a pivoted tongue, and a twisted wire member forming an anchor pointing in the same direction as the tongue and pivoted to the latter.
2. In a belt-buckle, the combination, with a suitable frame, of the pivoted tongue composed of two wires twisted together, one end of the wires forming the tongue-teeth and the other ends terminating in eyes, and the anchor

composed of two wires twisted together, one end of the wires forming the anchor-teeth and 15 pointing in the same direction as the tongue-teeth, and the other ends terminating in pintles which extend through the said eyes and are pivoted to the said frame.

In witness whereof I hereunto set my hand 20 in the presence of two witnesses.

MARGARET LA GORCE STREETER.

Witnesses:

J. Ross COLHOUN,
C. T. BELT.
